US00D554299S

(12) **United States Design Patent** (10) **Patent No.:** **US D554,299 S**
Ragonetti et al. (45) **Date of Patent:** **** Oct. 30, 2007**

(54) **BIRDCAGE ATTACHMENT**

(75) Inventors: **Peter Ragonetti**, Brooklyn, NY (US);
Ryan Rutherford, Rutherford, NJ (US); **Jonathan Willinger**, Tenafly, NJ (US)

(73) Assignee: **JW Pet Company, Inc.**, Teterboro, NJ (US)

(**) Term: **14 Years**

(21) Appl. No.: **29/266,260**

(22) Filed: **Sep. 15, 2006**

Related U.S. Application Data

(60) Continuation-in-part of application No. 29/264,790, filed on Aug. 17, 2006, which is a division of application No. 29/230,071, filed on May 16, 2005, now Pat. No. Des. 530,866, which is a division of application No. 29/180,987, filed on May 2, 2003, now Pat. No. Des. 508,589, which is a continuation-in-part of application No. 10/371,646, filed on Feb. 21, 2003, now Pat. No. 6,971,332, application No. 29/266,260, which is a division of application No. 29/230,071, filed on May 16, 2005, now Pat. No. Des. 530,866, which is a division of application No. 29/180,987, filed on May 2, 2003, now Pat. No. Des. 508,589, which is a continuation-in-part of application No. 10/371,646, filed on Feb. 21, 2003, now Pat. No. 6,971,332, application No. 29/266,260, which is a continuation-in-part of application No. 11/245,556, filed on Oct. 7, 2005, and a continuation-in-part of application No. 11/182,380, filed on Jul. 15, 2005, which is a continuation of application No. 10/371,646, filed on Feb. 21, 2003, now Pat. No. 6,971,332.
